Matthew D. Brown
Letter's Patent dated October 1st 1830

The schedule referred to in these Letters Patent, is making part of the same, containing a description in the words of the said Matthew D. Brown himself, of his improvement in Ferry Boats

Be it known that I, Matthew D. Brown of Mason County, State of Virginia, have made an improvement in Ferry Boats, & in propelling the same, which is described as follows:

This Ferry Boat, with the apparatus used in propelling it, consists of the following principal parts: 1st The Boat, 2^d The lee board, 3rd The uprights & rollers for regulating the depth of the lee board, 4th The pulleys & windlasses for steering the boat; 5th The Windlasses for raising & lowering the Lee board, 6th The Skiff or float for supporting the sway of the rope. 1st The Boat is constructed in the ordinary manner of Ferry Boats, adapted to the purposes required. 2^d The lee board is made of nearly the length of the boat about 5 feet deep, adopted to the current of the water - It has three standards, fastened to it & extending above & somewhat more than the depth of the Lee Board -

3rd The uprights & rollers for regulating the depth to which the Lee board shall enter the water. There are three uprights fastened to the sides of the Boat, one near each end & one near the middle on each of these uprights is a roller, turning on an axle, supported by two arms connected with the uprights.

By between which & the uprights the Standards of the Ice Board pass. On the lower edge of the gunnel of the Boat, presented to the stream are three friction rollers, against which the Ice Board passes, when raised or lowered.

5th. The Windlass for raising & lowering the Ice Board is fixed in a near the centre of the boat. A fixed rope, fastened to the centre, Standard (which slides in a groove) is wound by the Windlass round a barrel; this rope passes thro' a block & pulley on which a weight can be hung for keeping it tight.

6th. The Skiff or float, is in the shape of a common Skiff, sharp at both ends, having a Mast in the centre, to the top of which the rope is made fast. The float is kept in its place & in a proper direction by short ropes fastened to the Main rope, above and below the float.

Operation. A rope or wire of sufficient length & strength is made fast at one side of the river or stream, at a proper height & distance: it is fastened to the ends of the float or floats. It then passes to an iron ring, where it is made fast. Another rope fastened to this ring passes round two pulleys one on each end of the Boat, & round the windlass for steering it, two or three times. This windlass is made permanent near the centre of the boat. The Ice Board is lowered by means of the windlass on a sled, according to the strength of stream or current, the head of the boat is put in a proper direction by means of the steering wheel; & the strength of the current operating on the Ice Board, forces the boat across the stream.

An Ice breaker or crusher, is placed in the front of the boat. It is made by bracing together two pieces of timber of sufficient length & strength at an angle of about 32°. The lower piece is made with iron-

550

The invention here claimed, is the fixing of a long
rope or wire on one side of a river or stream, & holding
up the rope or wire by floats: the mode of raising & de-
pressing the Ice Boats; the mode of steering the boat, & the
icebreaker. For a further illustration of my
invention I refer to the Model & drawing of the
same deposited in the Patent Office.

In testimony that the foregoing is
a true Specification or description of my invention, I have
subscribed my name before two Witnesses & made Oath to
the same at the County of Mason this 17th day of July
1830.
